UNITED STATES PATENT OFFICE.

EDWIN R. FERRY, OF NEW HAVEN, CONNECTICUT.

SASH-FASTENER.

SPECIFICATION forming part of Letters Patent No. 336,100, dated February 16, 1886.

Application filed October 10, 1885. Serial No. 179,465. (No model.)

To all whom it may concern:

Be it known that I, EDWIN R. FERRY, a citizen of the United States, residing at New Haven, in the county of New Haven and State 5 of Connecticut, have invented certain new and useful Improvements in Sash-Fasteners; and I do declare the following to be a full, clear, and exact description of the invention, such as will enable others skilled in the art to 10 to which it appertains to make and use the same, reference being had to the accompanying drawings, and to the letters and figures of reference marked thereon, which form a part of this specification.

15 This invention relates to an improvement in sash-fasteners, the object being the production of a fastener that will act automatically and firmly secure the window in its closed position.

20 Fasteners as usually constructed employ one or more springs, which are liable to break and render the fastener useless.

My improvement overcomes this difficulty; and it consists in the construction of its parts, 25 as fully described hereinafter.

Figure 1 represents a view of the sash-fastener as applied to a window; Fig. 2, a sectional view of the case B and cam-shaped piece C; Fig. 3, the set-screw detached; Fig. 4, a plan view of 30 the case B.

A represents one part, which is made from any suitable metal, and is designed to be secured to the lower sash at its top. It is set in so as to come flush with the top and side of 35 the sash, as seen in Fig. 1. On one side, *a*, one or more notches, *b*, are provided. The top part, *c*, is secured to the sash by screws or otherwise. The other part of the fastener is composed of a metal case, B, having ears 40 *d*, perforated for the introduction of screws or their equivalent, for the purpose of fastening to the upper sash. Inside the case is a cam-shaped piece, C, hinged at *e*, so that by its own weight the point *f* will project beyond 45 the case, as shown. At the top of the case a longitudinal slot is made, through which a set-screw, *H*, is introduced into the cam-shaped piece C as a means of adjustment. When the window is closed, the point *f* of the 50 cam-shaped piece C firmly bears upon the inclined point *h* of the part A, firmly securing

the sash, which cannot be raised from the outside. When it is desired to raise or lower the sash, the set-screw *H* is pressed forward, thereby throwing the point *f* out of the path 55 of the part A. The sash can then readily be raised. The window can be lowered without interfering with the set-screw *H*, as in the downward movement the cam-shaped piece C acts automatically by its own weight, as when 60 in lowering the sash the points *g* strike the point *f* the said point *f* is thrown inward and falls by its own weight into the notches *b*, and prevents the lower sash from being raised. If it is desired to secure the cam-shaped 65 piece C in a position where it will not act as a means of locking the sash, it may be adjusted by the set-screw *H*, so that the point *f* will be entirely within the case, firmly held there out of the way of the part A. As a convenient means of accomplishing this, I cut away from each side the center of the under side of the head of the set-screw, leaving a slight projection, *i*. When the cam-shaped piece C is in operation, the said part *i* of the set-screw 75 falls into the slot in the case.

When it is desired to lock the cam-shaped piece within the case, turn the set-screw until the part *i* comes crosswise of the slot, which will prevent the cam-shaped piece C 80 or any part of it from projecting from the case, as the set-screw as adjusted firmly holds it in place. The sash can then be freely raised or lowered.

If at any time it becomes desirable to lower 85 the upper sash a short distance for ventilation, the lower sash can still be locked, if desired, as also the upper sash be prevented from being further lowered from the outside. If the upper sash, to accomplish this desire, 90 be lowered so that the point *f* of the cam-shaped piece C falls into either of the notches *b*, the sash is firmly locked in that position—that is, the lower sash is prevented from being raised and the upper sash from being lowered 95 without the aid of the set-screw *H* from a person inside.

The fastener, as described, is automatic in its action and firmly secures the sash. It is simple in its construction and cheap.

Having thus fully described my invention, what I desire to secure by Letters Patent is—

The herein-described sash-fastener, consisting of the part A, provided with notches *b*, the case B, and cam-shaped piece C, having a projection, *f*, to engage the notches *b*, and 5 hinged to the case B, the set-screw H, having a projection, *i*, working in a slot in the said case B, all as and for the purpose specified.

In testimony whereof I affix my signature in presence of two witnesses.

EDWIN R. FERRY.
